KILN.

1,263,620.

Specification of Letters Patent. Patented Apr. 23, 1918.

Application filed September 25, 1916. Serial No. 122,136.

To all whom it may concern:

Be it known that I, HALVER R. STRAIGHT, a citizen of the United States, residing at Adel, in the county of Dallas and State of Iowa, have invented new and useful Improvements in Kilns, of which the following is a specification.

My invention relates to improvements in kilns or ovens, and more particularly to 10 down draft kilns adapted to use producer gas as fuel.

The object of my invention is to simplify the construction of kilns or ovens and to increase the efficiency thereof by eliminating 15 the use of bag or flash walls therein.

Another object of my invention is to simplify the means of installing apparatus for burning gas in down draft kilns.

A further object is to provide more effective means for controlling the distribution 20 of heat in case of storm or unequal loading of different parts of the kiln.

A further object is to economize space by arranging flues and other accessories above 25 the kiln, instead of at the side thereof, thereby accommodating a larger number of kilns within a given space.

A further object is to utilize shorter flues from the source of gas supply to the point 30 of combustion and thus save heat units now lost by radiation.

In the drawings, Figure 1 is a fragmentary central sectional view of a kiln embodying my invention; Fig. 2 is a detail plan view of the nozzles forming the gas burners and the influents leading thereto; Fig. 3 is a fragmentary bottom view of the same; Fig. 4 is a detail sectional view taken on the lines 4-4 of Fig. 1, and illustrates the valve in 40 one of the gas nozzles; and Fig. 5 is a perspective view in detail of my gas nozzle and air nozzle, and shows the manner in which said nozzles are assembled to form a burner.

Referring to the drawings, I have used the 45 reference numeral 10 to indicate the wall of the kiln and 11 the crown thereof. The base, which may be of ordinary construction, is omitted. The interior of the kiln is unobstructed by bag or flash walls and is capable 50 of receiving a maximum supply of ware to be baked. By placing the producer gas main 12 and air supply pipe 13 above the crown of the kiln, I economize space and permit the grouping of a maximum number 55 of kilns on a given area. Through the crown 11 of the kiln, I form a plurality of

openings 14, which are preferably arranged in a horizontal circle about the center of said crown. Downwardly flaring air nozzles 15 extend into said openings and are furnished with air from an annular air distributor 16, located above the crown and connected with the air main 13. This main may lead through any suitable heating apparatus and may be provided with a fan or other device (not shown) to impart pressure to the air in the distributor 16. A gas drum 18 is mounted upon the top of the crown 11 with its base encircled by said annular air distributor 16, and a gas conduit 19 forms an influent through the side of the drum from the gas main. Gas nozzles 20 lead obliquely downward from the base of the drum into the openings 14. The lower end of each of these nozzles passes through the inner side 75 of one of the air nozzles and opens within and slightly above the mouth of said air nozzle. It will thus be seen that the gas and air nozzles form burners which direct the combustible mixture of gas and air downward 80 and outward toward the wall of the kiln. The proportion of gas and air issuing from the burners may be varied at will by regulating gate valves 21 in the air nozzles 15 and the swinging valves 22 in the gas nozzles, it being, of course, desirable to supply air in excess of the amount required for the initial combustion at the burner. By reference to Figs. 1 and 3, it will be seen that the air is delivered to the burner above and on both sides of the jet of gas and it will 85 also be noted that said valves 21 and 22 are arranged so that in any position of their adjustment air will pass above the gas and said air and gas will not be deflected from their oblique course toward the wall of the kiln. As the air is heavier than the gas, I believe, from past experience, that the presence of free air above the gas in the crown 90 of the kiln will facilitate subsequent combustion in the kiln. The valves 21 and 22 may also be employed to cut off the supply of air and gas from part of the burners, while others are in use. This use of the valves is often advantageous for the reason 95 that it provides for properly distributing the heat in stormy weather or when the bulk of ware to be fired is in one side of the kiln.

To prevent unnecessary radiation between the nozzles and the crown of the kiln, and 110 also to compensate for unequal expansion between the materials of which the same are

constructed, I place in the openings 14 between the nozzles and the kiln crown 11 a collar 23 of non-heat conducting material, such as asbestos.

5 I provide for cleaning the kiln by burning out accumulations of carbon through the gas distributing drum 18. Said drum 18 has an opening 24 in the top thereof, which is normally closed by a cover 25. When the kiln 10 is not in use, this cover may be removed and the drum will serve as a chimney through which soot and other products of combustion may be burned out.

Having described my invention, what I 15 claim as new and desire to protect by Letters Patent, is:

1. A kiln, provided with a series of openings in the crown thereof for the introduction of gas and air, in combination with a 20 gas drum above said crown, an annular air distributor about the base of said drum, a series of air nozzles leading from said distributor into the openings in the crown of said kiln, and a series of gas nozzles leading from said drum and discharging within said air nozzles.

2. A kiln, provided with openings in the crown thereof, in combination with a gas distributing drum above the crown, an annular air distributing conduit around said drum, a series of flaring air nozzles leading from said conduit into the openings in the crown of said kiln, and a series of gas nozzles extending radially downward and outward from said drum and discharging within said air nozzles.

3. A kiln, provided with a series of openings at the top of the crown, in combination with a plurality of burners, each consisting of an air nozzle and a gas nozzle discharging within said air nozzle, said nozzles being arranged to direct air and gas obliquely downward toward the wall of the kiln, and controlling valves in said nozzles.

4. A down draft kiln, provided with a gas burner located in its crown, a radial gas distributor and an annular air distributor located above the crown, and gas and air inlets leading respectively from said gas and air distributors to said burner.

5. In a down draft kiln, provided with a series of openings in the crown thereof for the introduction of gas and air, a series of burners arranged in a horizontal circle 55 having nozzles directed obliquely toward the

wall of the kiln and located within said openings, an air influent pipe and a gas influent pipe leading to said burners.

6. In a down draft kiln, provided with a series of openings in the crown thereof for 60 the introduction of gas and air, a series of burners arranged in a horizontal circle having nozzles directed obliquely toward the wall of the kiln and located within said openings, a gas influent pipe leading to said 65 burners, and an air influent pipe communicating with said burners and discharging above said gas pipe.

7. In a down draft kiln, provided with a series of openings in the crown thereof for 70 the introduction of gas and air, a series of burners having nozzles directed obliquely toward the wall of the kiln and located within said openings, an air influent pipe and a gas influent pipe leading to said burners. 75

8. In a down draft kiln, provided with a series of openings in the crown thereof for the introduction of gas and air, a series of burners having nozzles directed obliquely toward the wall of the kiln and located within 80 said openings, a gas influent pipe leading to said burners, and an air influent pipe communicating with said burners and discharging above said gas pipe.

9. In a down draft kiln, provided with a 85 series of openings in the crown thereof for the introduction of gas and air, a series of burners located within said openings, a gas influent pipe leading to said burners and an air influent pipe discharging into said burners above said gas pipe.

10. In a down draft kiln, provided with a series of openings in the crown thereof for the introduction of gas and air, a series of burners located within said openings, air influent pipes communicating with each burner and discharging at the inner part of said openings, and gas influent pipes projecting within and discharging immediately beneath 95 said air influents.

11. A kiln provided with openings at the top of the crown, air nozzles extending into said openings, a gas distributing drum having an opening at the upper end thereof, a closure for said opening, and gas nozzles 105 leading downward from said drum and discharging within said air nozzles.

Whereof, I have hereunto subscribed my name to this specification.

HALVER R. STRAIGHT. 110
